UNITED STATES PATENT OFFICE.

ISAAC E. PALMER, OF MIDDLETOWN, CONNECTICUT.

LONGITUDINAL STRETCHER FOR HAMMOCKS.

SPECIFICATION forming part of Letters Patent No. 612,991, dated October 25, 1898.

Application filed November 19, 1897. Serial No. 659,095. (No model.)

To all whom it may concern:

Be it known that I, ISAAC E. PALMER, of Middletown, in the county of Middlesex and State of Connecticut, have invented a new and useful Improvement in Longitudinal Stretches for Hammocks, of which the following is a specification.

My invention relates to an improvement in longitudinal stretchers for hammocks; and it consists in a device arranged to coöperate with the hammock-supports for holding the opposite ends of the hammock at such a distance apart as to give to the hammock the desired pitch with respect to a vertical line.

15 A practical embodiment of my invention is represented in the accompanying drawings, in which—

Figure 1 represents a hammock in side elevation provided with an extensible stretcher 20 of rigid material. Fig. 2 is an enlarged cross-section through the stretcher, and Fig. 3 is a view in side elevation representing an extensible stretcher of flexible material.

The hammock-body is denoted by A, its 25 supporting-cords at its opposite ends by a' , and the supporting-ropes leading, respectively, from the head supporting-cords and foot of seat-frame to the point from which the hammock is primarily supported are denoted by $a^2 a^3$.

In the form shown in Fig. 1 the primary points of support (denoted by B B') are located a distance apart less than that which would be at all times desirable if the hammock were to be allowed to take its natural 35 curve when suspended therefrom, and in this instance I interpose the extensible stretcher of some suitable rigid material—such, for example, as wood—between the supporting-ropes $a^2 a^3$ and the supporting-cords at the head and foot of the body of the hammock.

The stretcher is here shown as formed of three sections C C' C², the sections C' C² being arranged to telescope within or slide along 45 a groove in the central section C. The central section consists of a pair of cheek-pieces c c', provided on their adjacent faces with grooves c² for the reception of the ribs c³ on the opposite faces of the sliding sections C' C².

50 A pair of clamps, each consisting of open U-shaped sections c⁴ c⁵, having a tongue-and-

socket interlocking engagement c⁶ at one end and a screw c⁷ at the opposite end for drawing the sections together, serve to tightly hold the sections C' C² in their several adjustments. 55

The sections C' C² are provided on their under sides with hooks c⁸ for the attachment thereto of the opposite ends of the hammock, and on their upper sides they are provided 60 with hooks or eyes c⁹ for the attachment thereto of one end of the supporting-ropes a² a³.

By means of this structure the ends of the hammock, when secured at or near the opposite ends of the stretcher and the latter extended, may be separated from one another 65 a distance much greater than the distance between the points of primary support and the hammock thereby caused to assume a position nearer the horizontal, as is commonly 70 preferred in case the occupant desired to sleep or rest without occupation. If, on the other hand, the occupant desires to read while sitting in the hammock, the stretcher may be contracted in length and the ends of the hammock thereby brought nearer together, causing 75 the hammock to assume a position nearer the vertical, and if a position still nearer the upright be desired the ends of the hammock may be shifted from their connections with 80 the stretcher at or near its ends to connections with it nearer its center.

When the primary points of support are located a distance apart equal to or greater than the distance which the hammock would assume when stretched in the position nearest the horizontal—as, for example, in the position shown at B² B³, Fig. 3—the stretcher (denoted by C³) may be made of flexible material—such, for example, as rope—and may be 85 stretched between the hooks at the ends of the suspension-cords at the opposite ends of the hammock. By making this stretcher C³ adjustable in length—as, for example, by carrying one of its ends through the eye of the hook at the foot end of the hammock and folding it back along the stretcher and connecting it therewith by a tilting eyepiece D, which will bind on the body of the stretcher when 90 strain is applied to it and which will slide 100 freely along the body of the stretcher when no strain is applied—the opposite ends of the

hammock may be adjusted nearer to or farther away from each other to suit the pitch desired, the supporting-ropes a^2 a^3 in this instance assuming a position nearer the horizontal as the ends of the hammock are drawn nearer together by the stretcher and approach the perpendicular as the ends of the hammock are permitted to separate from one another.

5 This longitudinal stretcher serves to give 10 the hammock the various pitches desired regardless of the distance between the points of primary support, and thus adds to its general utility, because of doing away with the necessity of finding points of primary support 15 a distance apart sufficient to stretch it in its position nearer the horizontal, as has heretofore been common.

What I claim is—

1. The combination with a hammock, of an 20 adjustable longitudinal stretcher for holding the hammock in the desired extended adjustment and swinging supporting devices attached to and extending upwardly from the stretcher for securing it to fixed supports at 25 different distances apart, whereby the hammock may be maintained in the desired extended adjustment and in alinement what-

ever be the distances apart of the fixed supports, substantially as set forth.

2. The combination with a hammock, of an 30 extensible and contractible stretcher arranged lengthwise of the hammock for holding the hammock in the desired extended adjustment and swinging supporting devices attached to and extending upwardly from the 35 stretcher for securing it to fixed supports at different distances apart, substantially as set forth.

3. The longitudinally-extensible stretcher-bar, comprising a central section formed of 40 cheek-pieces and sliding sections interposed between the cheek-pieces, the sliding sections and the cheek-pieces being provided, the one with a tongue and the other with a groove to receive the tongue and clamps, consisting of 45 separable interlocking sections, for holding the cheek-pieces in close engagement with the sliding sections to secure them in their various adjustments, substantially as set forth.

ISAAC E. PALMER.
